UNITED STATES PATENT OFFICE.

WILLIAM WALLACE KEMP AND WILLIAM H. VAN HORN, OF BALTIMORE, MARYLAND.

BURNER.

1,074,626.

Specification of Letters Patent.

Patented Oct. 7, 1913.

Application filed April 26, 1913. Serial No. 763,761.

To all whom it may concern:

Be it known that we, WILLIAM WALLACE KEMP and WILLIAM H. VAN HORN, citizens of the United States, residing at Baltimore, in the State of Maryland, have invented new and useful Improvements in Burners, of which the following is a specification.

This invention relates generally to gas burners, but more particularly to the tips or nozzles therefor, and has for its object to provide a burner for use for cloth singeing, for floating or sweating the end seams of tin cans, and for like uses.

Another object of the invention is to provide a burner nozzle or tip which will give a uniform flame throughout the series or battery of tips upon the pipe-manifold.

In carrying out this object the invention comprises broadly a nozzle having a gas collecting chamber communicating through a very small passage or perforation with the manifold from which the gas is supplied, a plug with narrow slits seated in the nozzle and closing the outer end of the collecting chamber, and a combustion chamber in the nozzle beyond the plug in which the ignition of the gases issuing from the plug takes place.

The invention contemplates, further, the peculiar construction of the nozzles whereby the combustion chambers of the same, when the nozzles are arranged close together in a row, intercommunicate so that when burning a continuous narrow sheet of flame is produced, and the entire line of nozzles is kept ignited.

The invention also embraces means for adjusting the width of the sheet of flame of the row of tips to accommodate cloth, cans and the like varying in width, such means comprising valves or the like for cutting off the flow of gas to any desired number of the end tips or nozzles.

Other objects and advantages of this improved nozzle will be understood from and brought out in the following detail description of this invention, and in the embodiment of the same shown in the accompanying drawings, in which,

Figure 1 is an elevation, partly broken away, of a burner inclined to show the top of the burner, and disclosing a straight line of burner nozzles or tips comprising part of the burner. Fig. 2 is an end elevation of the same. Fig. 3 is a detail, enlarged, fragmentary, sectional view of the burner. Fig.

3^c is a detail longitudinal section through one of the end nozzles or tips taken at right angles to the showing in Fig. 3. Fig. 4 is a transverse sectional view through the burner 60 taken centrally through one of the nozzles and showing the soft flame produced. Fig. 5 is a similar view disclosing a slightly different form of plug and the thin needle flame produced. Fig. 6 is a top plan view of 65 one end of the burner showing a slight modification in the arrangement of the nozzles or tips, the same shown in staggered relation. Fig. 7 is a detail fragmentary, sectional, enlarged view of the burner showing a modified form of tip or nozzle applied thereto. 70 Similar characters of reference designate corresponding parts throughout the several views of the drawings.

In the accompanying drawings showing 75 the present embodiment of the invention the numeral 10 designates a pipe-manifold shown as cylindrical in form although any desired shape may be given the same. This manifold 10 is threaded at one end 11, for 80 attachment to a suitable source of gas supply, may be of any desired length, and is closed at its outer end in any suitable manner, as by a cap 10^a shown in Fig. 1. In one side of the manifold 10, preferably the upper side, as shown, is a longitudinal row of closely arranged tips or nozzles 12 through which the gas issues from the manifold 10.

With special reference to Fig. 3 of the drawings, it will be noted that each tip or nozzle 12 comprises a cylindrical casing providing therein a gas collecting chamber and being reduced at its inner or lower end to provide a supporting shank or neck 13 communicating with the interior of the casing. 95 The lower end of the neck 13 is threaded or otherwise suitably secured in the side of the manifold 10, and is closed at its lower end by a disk 14 preferably formed integrally with the neck 13 having but a single 100 small passage or perforation 15 extending centrally therethrough. The perforation 15 is the sole source of communication between the interior of the manifold 10 and the gas collecting chamber in the casing, and the 105 perforations 15 are of uniform size throughout the entire line of nozzles.

The casing of the tip or nozzle 12 is provided in its outer end with a counterbore, whereby to provide a shoulder 16 upon 110 which is seated a plug 17. The plug 17 is adapted to close the outer end of the gas

collecting chamber and is provided with a plurality of radially extending and relatively narrow slits, the slits extending from face to face of the plug and from a point 5 near the central axis of the plug to the periphery thereof. The casing of the nozzle 12 is carried beyond the outer face of the plug 17 to provide a combustion or ignition chamber in the outer end of the nozzle. 10 In Fig. 1 of the drawings it will be seen that the nozzles or tips 12 are arranged in a straight row from end to end of the manifold 10, and in Fig. 6 of the drawings the nozzles are shown as arranged in a row but 15 in staggered relation to one another. For the purpose of intercommunicating the ignition or combustion chambers of the nozzles, the casings of the nozzles 12 are cut away at their outer ends and adjacent sides 20 to provide recesses 18 diametrically opposed as shown in Fig. 1, or arranged at angles to one another at 18¹ as shown in Fig. 6. In both instances the recesses 18 are formed in the adjacent or touching sides of the nozzles 25 so that the combustion chambers of the entire line of nozzles are in communication with one another. It will, of course, be understood that the end nozzles are provided with uninterrupted walls 18², as shown in 30 Figs. 1 and 6 on the nozzles located at the ends of the manifold.

To admit the reducing of the width of flame, or the length of the flame longitudinally of the manifold, any desired number 35 of the nozzles or tips 12 at each end of the manifold are provided with valves or the like admitting the cutting off of the gas to these end nozzles or tips. In Figs. 1 and 2 of the drawings the five last nozzles or tips 40 12 at each end of the manifold 10 are provided with needle valves 12^a having enlarged heads on their outer ends for engagement by the fingers to regulate the valves. From Figs. 3 and 3^a it will be seen 45 that the needle valves 12^a are threaded through one side of the necks 13 of the nozzles or tips 12, project across the openings in the lower ends of the necks 13 and, when closed, fit into the recesses or seats 12^b formed 50 in the opposite sides of the necks 13. The valves 12^a are of a thickness sufficient to completely close the openings through the necks 13 and completely shut off the flow of gas to the tips 12. If desired the entire line 55 of tips 12 may be provided with these valves 12^a so as to regulate the flame across the entire line of tips.

From Figs. 3 and 4 it will be noted that in the preferred construction the plugs 17 60 have imperforate central portions, the same providing an abutment for the stream of gas passing up through the small perforation 15, and also preventing the needle-like formation of the flame burning at the nozzle. 65 This type of burner nozzle is peculiarly

adapted for use for singeing cloth since the flame produced, as seen in Fig. 4, is a soft tapering flame relatively thick and, when the burners are arranged in a row as shown in Figs. 1 and 6 they produce a relatively 70 long uninterrupted sheet of flame.

From Fig. 5 of the drawings it will be noted that the plug 17¹ may have a central or axial perforation 19 through which the gas issues in a fine stream. This fine stream 75 of gas when ignited produces a needle-like flame which draws in or collects the radial film of gas issuing from the plug so that the entire flame has the appearance shown in Fig. 5 of the drawings wherein a very narrow and elongated flame of needle-like appearance is produced. When these burners, shown in Fig. 5, are arranged in rows as shown in Figs. 1 and 6, the result will be a 80 row of closely arranged needle-like flames.

Should for any reason the flame cease to burn in the combustion chamber of any one of the nozzles and the supply of gas continue to flow through the nozzle, the gas will again immediately become ignited by 85 the entraining of the gas through the adjacent recesses 18 in the sides of the combustion chambers. Thus the burning of all of the nozzles or tips in the row is insured during 90 the operation of the burner.

In operation the gas in the manifold 10 passes through the relatively small perforations 15 in the tips of the burners 12 and into the gas collecting chambers in the casings thereof, the perforations 15 being 100 of uniform size throughout the line of burners insures a uniform distribution of the gas throughout the entire line of burners. In the chamber of each of the burners 12 the gas is permitted to expand and the stream 105 of gas issuing from the perforation 15 cannot strike the burner plug or disk 17 at one point with any greater force than at another so that the flame will be uniform over the entire area of each tip and the entire line 110 of nozzles. The collected gas within the casing 12 passes upwardly and outwardly through the relatively narrow slits in the plug 17 and passes into the combustion chamber of the nozzle in fine sheets or films. 115 When in action, these thin sheets or films of gas are ignited in the combustion chamber, and since the central or middle portion of the plug 17 is solid or imperforate a flame such as disclosed in Fig. 4 will be produced.

When the plug 17¹ shown in Fig. 5 is used in the nozzle or tip, then the gas issues through the relatively small central perforation 19 in a thin jet drawing into it, the 120 surrounding films of gas issuing through the slits in the plug 17¹. Thus the needle-like flame of Fig. 5 is produced.

In Fig. 7 of the drawings is disclosed a 125 modification in the structure of the burner 130

nozzle or tip wherein means is provided for controlling the flow of gas from the manifold 10¹ into the burner tips or nozzles. From this figure it will be seen that each tip or nozzle comprises a casing 12¹ fitted in a corresponding opening in the upper side of the manifold 10¹ and being reduced at its lower end to provide a neck or stem 13¹ threaded or otherwise suitably secured 10 through the lower wall of the manifold 10¹. A small opening or passage 15¹ is provided in the side of the neck 13¹ through which gas passes into the neck and through a narrow passage 20 leading from the lower end of 15 the gas collecting chamber in the casing 12¹, the body of the nozzle being provided with a valve seat at the lower end of the passage 20 adapted to receive a needle valve 21 carried upon the upper end of a screw plug 22 threaded in the lower end of the neck or 20 stem 13¹. As will be seen from Fig. 7 the stem or neck 13¹ opens through the bottom of the manifold 10¹, such arrangement being had whereby easy access may be gained to 25 the screw plug 22 for adjusting the size of the flame while burning. With this modified arrangement or addition to the preferred form of burner, the entire line of flame may be adjusted to the desired height; 30 so that in any class of machine or work in which it is desirable to taper or incline the flame, or vary the intensity of the heat at any point in the line of flame, this may be done.

35 When it is desired to reduce the width of the line of flame to accommodate cloth varying in width, it is only necessary to close the valves 12^a of the desired number of the end tips 12 at each end of the manifold.

40 It is of course understood that various changes or modifications may be made in the structure of the burner to suit the conditions under which the burner is to be used, such changes or modifications being 45 comprehended in the scope of this invention as defined in the appended claims.

What is claimed is—

1. In combination with a pipe manifold, of a plurality of nozzles carried thereby, 50 each of said nozzles comprising a casing, having a gas collecting chamber, and an ignition chamber, an apertured plug arranged in the casing between said chambers, and a stem upon the inner end of said casing engaging the manifold and having a small perforation therein constituting a source of communication between the manifold and the collecting chamber.
2. In a burner, and in combination, a 55 pipe-manifold, a plurality of nozzles arranged in a row upon one side of the pipe-manifold, each of said nozzles having a gas collecting chamber communicating with the manifold through a relatively small opening, said nozzle having an ignition

chamber at its outer end and an apertured plug disposed in the nozzle between said chambers.

3. A nozzle for gas burners comprising a casing provided with a depending stem, said stem having a single relatively small perforation through which gas may be introduced into the casing, and an apertured plug arranged in the casing and providing therein a gas collecting chamber and an ignition chamber.

4. In a burner and in combination a pipe-manifold, and a plurality of nozzles arranged in a row upon one side of the manifold, said nozzles having abutting ignition chambers in their outer ends and provided with recesses in their adjacent sides whereby to establish intercommunication between said ignition chambers.

5. In a burner, a manifold, and a plurality of nozzles carried upon one side of the manifold, said nozzles being arranged in a row and abutting at their adjacent sides, said nozzles being provided in their outer ends with combustion chambers and having recesses in the walls of said chambers, whereby to establish intercommunication between the combustion chambers of said nozzles.

6. In a burner, and in combination, a pipe-manifold, and a row of abutting nozzles carried at one side of the manifold, and having recesses in their abutting sides and at their outer ends whereby to intercommunicate the combustion chambers of the nozzles.

7. In a burner, and in combination, a pipe manifold, and a staggered row of abutting nozzles carried upon one side of the manifold and having their abutting sides recessed whereby to establish intercommunication between the nozzles.

8. In a burner of the class described, and in combination, a manifold, a row of nozzles mounted on the manifold and communicating therewith and having their adjacent sides abutting, said nozzles having open-ended combustion chambers in their outer ends wherein the ignition of gas from the manifold takes place, and means for regulating the supply of gas independently to said nozzles from without the manifold.

9. In a burner of the class described, and in combination, a manifold, a plurality of nozzles carried by the manifold and having relatively small openings therein communicating with the manifold and having their adjacent sides abutting, and separate valves carried upon the nozzles for regulating the passage of gas through said small openings from without said manifold.

10. In a burner, a manifold, a plurality of nozzles on the manifold having their adjacent sides fitting closely together, each of said nozzles having a relatively small

opening communicating with the manifold through which gas may be supplied to the nozzle, and valves carried on said nozzles exteriorly of said manifold for controlling the passage of gas through said small openings.

11. A burner comprising a manifold, a longitudinal row of nozzles mounted on the manifold with their adjacent sides abutting and having open outer ends providing combustion chambers thereat wherein the ignition of the gas from the manifold takes

place, and means exteriorly of the manifold for controlling the flow of gas independently through the nozzles.

15 In testimony whereof we have hereunto set our hands in presence of two subscribing witnesses.
